[57] ABSTRACT

Method of knitting run proof courses on multifeed circular knitting machines comprising dividing the needles one by one into two groups and forming loops of at least a single yarn on the needles of one group dial ribs in the space above the needles of the second group. The second group of needles during this step are withdrawn below the ribs. Thereafter loops are formed with at least a single yarn on the needles of the second group so that the yarn at least crosses over the loops of the first needles. Thereafter the ribs are withdrawn through the loops of the second needles and then all the loops are knocked off.

METHOD OF KNITTING AN ANTI-LADDER STITCH COURSE

BACKGROUND OF INVENTION

The present invention relates to a method of knitting anti-run courses on a multi-feed circular knitting machine.

The methods presently used to knit anti-run or anti-ladder courses on circular knitting machines either require modification of the machine itself by the use of special needles or other loop forming means, or are characterized by resulting only in limited anti-run properties. One of the recent methods of forming anti-run courses is based on the principle of forming double loops which are secured against unravelling by being pulled through the loops of the last normally knit course. The double loops are further secured by underlaying another yarn forming still another loop in the adjacent wales. Another technique is also known which is similar to the preceding one with the difference that the anti-run loops are secured by additional yarn loops in the neighboring wales.

The aforementioned methods are simple and effective. However, they have the disadvantage that specially modified sinkers are needed to form the loops. It was also necessary to introduce an extra yarn and guide in those feeds which form the anti-run course.

It is the object of the present invention to provide a method for knitting anti-run courses which overcomes the disadvantages and defects of the prior art techniques.

It is another object of the present invention to provide a method for forming anti-run courses on a multi-feed circular knitting machine which does not require the use of special knitting instruments, or special modifications.

It is also an object of the present invention to provide a novel method of knitting run-proof courses on hosiery which is simpler, more effective and faster than the prior art.

These objects, others and numerous advantages will be seen in the following disclosure of the present invention.

SUMMARY OF THE INVENTION

According to the present invention a method of knitting anti-run loop courses in a multifeed circular knitting machine is provided comprising dividing the needles one by one into two groups and forming on the needles of one group loops of at least a single yarn, wherein the yarn is held by auxiliary instruments such as dial ribs in the space above the needles of the second group. The second group of needles during this step are withdrawn below the yarn held by the knitting instruments. Thereafter loops are formed with at least a single second yarn on the needles of the second group, while maintaining the first yarn on the needles and knitting instruments. The second yarn is formed so as to at least cross the loops formed on the first needles. Thereafter, the first yarn held on the knitting instruments are withdrawn through the loops of the second group of needles and all the loops are then knocked over, and released.

Preferably the yarn of the second group is laid freely across the loops of the first needle, although it may be looped with the loops of the first needle. It may be advantageous to employ two yarns on the second group

of needles, one which is laid freely while the other is looped with the loops of the needles of the first group.

The method also includes the possibility of adding additional yarns before or after the formation of the loops on the second needles, or even before the formation of the loops partially held by the knitting instruments. In addition it may be preferable to provide one or more tuck loops with the yarn held by the auxiliary knitting instruments.

Full details of the present invention are set forth in the following disclosure and will be seen in the attached drawings.

BRIEF DESCRIPTION OF DRAWINGS

In the drawings:

FIG. 1 is a diagrammatic view of the first step of the development of the anti-run course showing yarn of a first feed looped on the needles of the first group of a 1 by 1 division and held on the associated dial ribs;

FIG. 2 is a view similar to that of FIG. 1 showing the first group of needles sunken, and the tuck looping of a second yarn feed system on the second group of needles;

FIG. 3 is another view showing a third step of the development showing the further knitting in of yarns of third yarn feed system drawn in the needles;

FIG. 4 is a similar view showing the successive drawing of the yarns gripped on the dial ribs;

FIG. 5 is a diagrammatic view of the anti-run course made in accordance with the method of FIGS. 1 - 4;

FIG. 6 is a view similar to FIG. 5 showing a modified form wherein the second yarn feed is omitted;

FIG. 7 is still another modified anti-run structure such as FIGS. 5 and 6 in which the second feed yarn is similar to that of the third feed system;

FIG. 8 shows another modification in which the third feed forms normal loops while a fourth yarn feed system is fed similarly to the preceding third feed; and

FIG. 9 is still another modification in which second and third feed systems knit similarly, and normal loops are formed on the first group needles and tuck loops are formed on the second group needles.

DESCRIPTION OF INVENTION

The present invention is described in connection with a multifeed rotary needle cylinder and dial machine, the cylinder of which is provided with a plurality of longitudinal grooves or tucks in each of which knitting needles having the conventional latches are movably arranged, while the dial is provided with a plurality of radial grooves in which knitting instruments such as dial ribs or needles are arranged to cooperate with the vertical knitting needles. In the drawing the knitting needles bear reference numeral 1 while the dial ribs bear reference numeral 2. The knitting machine comprises the usual cam systems, feed means, etc., each of the needles being provided with associated sinkers, selectors and jacks, and having butts by which they can be moved. The dial is provided also with conventional control rings and cams. For the purposes of the present invention an eight feed machine is employed, although a lesser number is possible. The needle cylinder is rotated about its central axis, denoted by the arrow S in the drawing. The dial ribs reciprocate with respect to the arrow S'.

The method of the present invention is illustrated with the formation of an anti-run or unravelling course being applied to a knit piece such as a stocking or tubular garment having a pattern made by dividing the needles into a 1 by 1 ratio, providing two groups of needles 1₁ and 1₂. Preferably all eight feeds are employed to make the knitwork which comprises a plurality of loop courses. The anti-run course is applied upon finishing a predefined length of material from a yarn seen in the drawings by the numeral P. In forming this anti-run course, the finishing is performed by the first four feeds while the fifth feed serves to knock-off the knitwork from the needles.

Turning now to the drawings the invention can best be understood with reference to the sequential state of operation in each feed course during the continued operation of the machine in the finishing process.

First Feed:

As seen in FIG. 1 the first feed provides a yarn P₁ which makes normal loops on the elevated needles 1₁ of the first group, while needles 1₂ of the second group remain in their bottom or sunken position holding the loops of the yarn P₁ in wales between the needles 1₁. Above the needles the dial ribs 2 are extended to hold the yarn P₁ fast and form loops in wales corresponding to the needles 1₂. The loops P held on the needles 1₂ were of course formed by the preceding feed.

Second Feed:

During this feed (FIG. 2) the needles 1₁ of the first group are extended only into the tuck position. Thus the yarn P₁ remains on the needle latch of these needles, and on the dial ribs 2. The second yarn P₂ is fed to all the needles. In doing so it is loaded onto the latches of the needles 1₁ of the first group and is thereupon drawn in to form from the yarn P₁ tuck loops while the needles 1₂ of the second group form normal loops from this second yarn P₂. In forming the normal loops the yarn P₂ is drawn through the loops of yarn P made by the last normal loop course.

Third Feed:

As seen in FIG. 3, two yarns P₃ and P₃' are laid during this feed stage. Needles 1₁ of the first group are extended into closing position and on their latches is laid only the yarn P₃. Needles 1₂ of the second group are lifted into a position higher than the closing position and both yarns P₃ and P₃' are laid in their latches. Meanwhile the yarn P₁ laid in the first feed remains held on dial ribs 2. During further knitting of the course, all the needles 1₁ and 1₂ are drawn in forming on needles 1₁ loops from yarn P₃; the yarn P₃' falling in the course of the drawings in movement behind the needle shafts of the needles 1₁. Yarn P₃' thus does not form loops but supports the loops of the yarn P₃ made on needles 1₁. On the other hand yarns P₃ and P₃' form double loops on the needles 1₂ of the second group.

Fourth Feed:

As seen in FIG. 4, the dial ribs 2 are extended in a manner similar to that in the formation of a double welt of a stocking, into the space corresponding to the needles 1₂ of the second group. The needles 1₁ and 1₂ are simultaneously raised with their latches in closed position so that the old loops made in the third feed remain below the latches of these needles (on the far side as seen in the figure). The latches then open. The loops of the yarn P₁ are then transferred from the dial ribs 2, by moving the ribs 2 in a radially opposite direction to that of the arrow S', so that the yarn P₁ is above and en-

ters into the latches of needles 1₂ which have then opened. Thereafter, the dial ribs 2 are moved in the direction of arrow S' and the needles 1₂ of the second group are simultaneously drawn in or downward. This transfers the yarn P₁ to the latches of needles 1₂. The needles 1₂ draw yarn P₁ through the previously made loops of yarn P₃ and P₃', forming further loops of the yarn P₁. The loops of yarn P₃ which are on the needles 1₁ are knocked over, by the downward and then upward movement of the needles 1₁. In the event knitting is carried on to form succeeding knit courses, the needles 1₁ of the first group are not brought into closing position, in the fourth feed course, so that they hold their loops in the latches.

Fifth Feed:

Upon lifting and lowering the needles 1₂ in the second group the knitwork is knocked-over from the needles 1₂ of the second group. Thus, as seen in FIG. 5 the method produces an anti-ladder or anti-run course.

The steps just described are illustrative of the inventive process. Many modifications may be made. For example, by omitting the second feed stage and the knitting of the second yarn P₂ while retaining the operation of the remaining feeds according to the preceding procedure, an anti-run course such as seen in FIG. 6 can be made.

Another possibility is shown in FIG. 7. Here the second feed is operated to knit the second yarn P₂ and a supplementary yarn P₂' in the same manner as the third feed, of the procedure described earlier. Meanwhile, in the third feed only that part of loops of yarn P₃ and P₃' which are formed on needles 1₁ of the first group are constituted; no loops of yarn P₃' being formed on the needles 1₂. The process may be further simplified by eliminating the supplementary yarn P₃' altogether. The elimination of yarn P₃' however reduces the resistance to unravelling and those loops which are not drawn through the loops previously made of yarn P₁ are not secured against ravelling. Nevertheless, even in this simplified method, the degree of anti-run characteristics is so considerable, in comparison to plain knitwork, that it is far superior. This may also be further enhanced by the formation of loops of differing length in the various knitwork courses.

A further modified version is seen in FIG. 8. Here the first two feeds perform the operation shown in FIGS. 1 and 2 while the third feed forms normal loops of yarn P₃ only on both the needles 1₁ and 1₂. Two yarns P₄ and P₄' are laid in the fourth feed so that double loops of yarn P₄ and P₄' are formed on needles 1₂ of the second group while only a single loop of yarn P₄ is laid on needles 1₁ of the first group. The supplemental yarn P₄' is freely laid across the loop on the needles 1₁ and secures it against unravelling. In the fifth feed loops of yarn P₁ are drawn through the double loops of yarn P₄ and P₄' and loops of yarn P₄ are knocked over the needles 1₁ of the first group. On a subsequent feed, loops of yarn P₁ are knocked over from needles 1₂ of the second group.

Still another procedure is seen in FIG. 9. Normal loops are formed in the first feed. In the second feed normal loops of yarn P₂ on needles 1₁ of the first group, while on needles 1₂ of the second group tuck loops are formed wherein the main yarn P remaining on the needles 1₂ constitute with yarn P₂ a double loop. In the third feed the same knitting operation is performed as in the second feed so that only yarn P₃ is laid on the

needles 1_1 of the first group while yarn P_1 , P_2 and P_3 are laid on the needles 1_2 of the second group. In the fourth feed loops of yarn P_1 are drawn through tuck loops from yarns P_1 , P_2 , and P_3 while simultaneously loops from yarn P_3 are knocked over from needles 1_1 of the first group. In a further feed, loops of yarn P_1 are knocked over from needles 1_2 of the second group.

From the foregoing it will be seen that broadly after the needles are divided one by one loops are formed of at least one yarn (P_1 or P_1 and P_3) on the needles 1_1 of one group while a portion of the yarn (P_1 or P_1 and P_3) are held by the auxiliary knitting instrument or rib 2 in the space above the needles 1_2 of the second group which are withdrawn. Thereafter, loops are formed of at least one yarn (P_2 , P_3 , P_3' , P_4 and P_4') on at least the needles 1_2 of the second group with this yarn at least passing or crossing the loops made on the needles of the first group. It may be preferred to employ two yarns for the second needles 1_2 , one yarn passing freely the other yarn forming loops also on the needle 1_1 . In the alternative a single yarn may pass freely or form loops on the needles 1_1 as well as on the needles 1_2 . After this the loops which are formed are knocked over, the yarn (P_1 , or P_1 and P_3) held on the auxiliary knitting means 2 being first withdrawn through the loops formed on the needles 1_2 of the second group over which the means 2 extend.

It is to be noted that in practicing the present invention it is possible to draw loops through a group of loops made on needles 1_2 of the second group, the drawn loops having been located on the dial ribs 2, or even on other auxiliary knitting instruments and formed in the space of another group of needles other than those of needles 1_2 . It is also possible to draw two or more loops simultaneously through other loops. For example, yarns P_1 and P_3 in this manner, according to the procedure of FIG. 8.

Since various modifications are possible, the present disclosure is to be taken as illustrative only and not limiting of the scope of the invention.

What is claimed:

1. The method of knitting anti-run loop courses in multifeed circular knitting machines comprising the steps of dividing the needles one by one into two groups, forming loops of at least a single first yarn on

45

the needles of one group, holding said first yarn on auxiliary knitting instruments in the space above the needles of the other group, the needles of the other group being withdrawn below said knitting instruments, forming loops of at least a single second yarn on at least the needles of the other group while maintaining said first yarn on said auxiliary knitting instrument, said second yarn at least crossing the loops formed on the needles of said one group, and thereafter knocking over the loops of each group, said first yarn held on said auxiliary knitting instrument being withdrawn through the loops formed on the needles of said second group prior to knock over.

2. The method according to claim 1 wherin the second yarn is laid freely across the loops of the needles of said one group.

3. The method according to claim 1 wherin the second yarn is laid to form normal loops on the needles of said one group.

4. The method according to claim 1 wherin a plurality of normal loop courses are laid prior to dividing the needles.

5. The method according to claim 1 wherin said second yarn comprises a pair of yarns one of which forms loops on the needles of said one and said other groups and the other of which forms loops on the needles of said other group and is laid freely across the loop of said one group.

6. The method according to claim 1 including laying a third yarn between the laying of said first and second yarns to form loops on the needles of said one group and the needles of the second group, while maintaining said first yarn on the auxiliary knitting instrument.

7. The method according to claim 1 including the step of laying at least a single fourth yarn between the laying of said second yarn and the knocking over of said loops, said fourth yarn forming loops on the needles of said other group, and at least crossing the loops formed on the needles of said one group.

8. The method according to claim 1 including the step of reinforcing the loops formed by withdrawing the yarn held on the auxiliary knitting instruments with at least one tuck loop, the yarn forming said tuck loop forming normal loops on the adjacent needles.
